UNITED STATES PATENT OFFICE.

CLARENCE SCHULDT, OF DES PLAINES, ILLINOIS.

ELECTRIC CORD SWIVEL CONNECTER.

Application filed March 27, 1925. Serial No. 18,725.

The present invention relates to an electric connector for holding together two electric cords, so that one may be rotated in relation to the other.

6 The device prevents the electric cord from becoming twisted, when used with various devices, such as electric irons.

Another very important object of the invention is to provide a connector of this nature, formed in two sections, joined together, so that one may rotate in relation to the other, each section being provided with means for engaging the wires of an electric cord, and said means being always in electrical connection with each other.

Another important object of the invention is to provide a device of this nature, which is exceedingly simple in construction, efficient and reliable in use, inexpensive to manufacture, strong, durable, not likely to become out of order, and otherwise well adapted to the purpose for which it is designed.

With the above and numerous other objects in view, as will appear as the description proceeds, the invention resides in certain novel features of construction, and in the combination and arrangement of parts as will be hereinafter more fully described and claimed.

30 In the drawing:

Figure 1 is a longitudinal section through the connector embodying the features of my invention;

Figure 2 is a plan view of one block thereof;

Figure 3 is a plan view of the other block thereof; and

Figure 4 is a fragmentary elevation of the connector, showing a portion in section.

40 Referring to the drawing in detail, it will be seen that 5 designates a block of insulating material, and 6 another block of insulating material. The block 5 is provided with a reduced externally threaded extension 7, 45 on one face thereof, and an annular flange 8 on the other face thereof. The block 6 is provided with a reduced extension 9 on one face thereof, over which is adapted to extend the flange 8 and a reduced externally threaded extension 10 on the other face thereof. Internally threaded caps 11 of insulating material are adapted to be received on the extensions 7 and 10, as is shown in Figure 1, and are provided with the central 55 openings 12, through which the cords may be passed. The block 5 is provided with a

central bore 13, aligning with the openings 12. A U-shaped conductor plate 14 is disposed in the bore 13 and the intermediate portion thereof is apertured for receiving a bolt 15, which extends through the bore 16 provided centrally through the block 6. The upper ends of the U-shaped conductor 14 are provided with offset extensions 16, fixed to the face of the block 5, by screws 17. The 60 other face of the block 5 has mounted thereon a pair of conducting brushes 18, held in place by screws 19. An opening 20 extends through the block 5, parallel to the bore 13. One conductor of the electric cord is engaged with the head of the bolt 15, or preferably with one of the screws 17. Preferably that screw 17 which is disposed farther from the opening 20. The other conductor of the electric cord is passed through the 70 opening 20 and attached to the adjacent screw 19.

75 A ring conductor 21 is mounted on the inner face of the block 6, being held in place by screws 22. A washer 23 is embedded in the inner face of the block 6 and surrounds the bore 16. A coil spring 24 is disposed about the bolt 15, and impinges against the washer 23, and the intermediate portion of the U-shaped conductor plate 14. 80 A pair of nuts 25 are threaded on the bolt for engaging the outer face of the block 6, so as to hold the blocks 5 and 6 assembled, as indicated in Figure 1, and placing the desired tension on the spring 24. An opening 26 is provided in the block 6, extending 90 parallel to the bore 16. One conductor of the other electric cord is attached to the bolt 15, being held in place by nuts 25, while the other conductor is passed through the 95 opening 26 and engaged with one of the screws 22. The brushes 18 are adapted to wipe over the ring 21, as one block is rotated with respect to the other. Thus, the complete connection is always maintained 100 between the two electric cords, so that they may be rotated with respect to each other and prevented from becoming twisted.

105 It is thought that the construction, operation, and advantages of this invention will now be clearly understood, without a more detailed description thereof. It is desired, however, to point out that various changes in the details of construction, in the combination, and arrangement of parts may be resort to, without departing from the spirit 110 or scope of the invention as hereinafter

claimed, or sacrificing any of its advantages.

Having thus described my invention, what I claim as new is:

A device of the class described including
5 a pair of blocks of non-conducting material, one of said blocks provided with a centrally located bore, an annular flange on one face, and a reduced externally threaded extension on the other face, a U-shaped conductor in
10 the bore having its ends offset, screws extending through the offset ends into the said block, the intermediate portion of the conductor being apertured, a pair of brushes disposed on the face of the said block, the
15 other block provided with a centrally disposed bore, a reduced extension on its inner face, and a reduced threaded extension on

its outer face, a ring disposed on the inner face of the last mentioned block, screws for holding said ring in place, a washer disposed on the inner face of said last mentioned block, said brushes adapted to wipe over said ring, a bolt extending through the aperture of the U-shaped conductor, through the bore of the second block, means for holding the bolt in place, a spring disposed between the washer and the intermediate portion of the U-shaped conductor and tensioned by said bolt, both of said blocks being provided with off-center openings, 30 and a pair of caps threadedly engageable with the reduced extensions of the blocks.

In testimony whereof I affix my signature.
CLARENCE SCHULDT.
